AIR CONDITIONING SYSTEM

Richard C. Jepertinger, Milwaukee, Wis., assignor, by mesne assignments, to Modine Manufacturing Company, Racine, Wis., a corporation of Wisconsin

Application August 26, 1935, Serial No. 37,923

12 Claims.

(Cl. 257—3)

This invention relates to air conditioning systems for homes and buildings.

It is an object of this invention to provide an air conditioning system which needs no distributing ducts and in which the conditioning of the air for each room is effected directly in or near the room as distinguished from past systems in which all of the conditioning was done at a central remote point.

Another object of this invention is to provide an air conditioning system in which either a cooling or a heating medium is pumped under pressure from a central source to a number of remotely located conditioning units to effect both a temperature modification and an air circulation and to be returned from such units back to the source at atmospheric pressure.

Another object of this invention is to provide an air conditioning system in which the temperature modifying medium is utilized to provide increased humidification when necessary, and in which the pressure of the temperature modifying medium controls the functioning of the humidifying means.

A further object of this invention is to provide an air conditioning system particularly applicable for installation in buildings and homes already in use.

With the above and other objects in view which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawings illustrate two complete examples of the physical embodiment of the invention constructed according to the best modes so far devised for the practical application of the principles thereof, and in which:

Figure 1 is a cross section through two rooms and part of the basement of a building illustrating one embodiment of this invention;

Figure 2 is a view partly in front elevation and partly broken away and in section through one of the conditioning units of the system;

Figure 3 is a side view of the conditioning unit with a portion broken away and in section; and

Figure 4 is a view of a modified unit partly in side elevation and partly broken away and in section through a conditioning unit of the exposed type suitable for buildings and homes already in use.

Referring now more particularly to the accompanying drawings in which like numerals indicate like parts throughout the several views, the numeral 5 designates a building having a basement 6 and rooms 7 to be supplied with conditioned air. Each room has one or more conditioning units, indicated generally by the numeral 8. These units may be of the built-in type shown in Figures 1, 2 and 3, or of the exposed type shown in Figure 4. The built-in construction is preferable, and is therefore shown as the preferred embodiment of the invention.

The built-in conditioning unit comprises an elongated upright stack or air chamber 9 concealed in the wall of the room it is to supply, and provided with an inlet opening 10 at its lower end and an outlet opening 11 in its upper end. The unit is so mounted in the wall of the room that its inlet opening is near the base board and its outlet opening is near the ceiling. Both openings are covered by a suitable grill 12 and the inlet opening also has a filter element 13 preferably arranged behind its grill.

Through the inlet opening 10, the air is taken off the floor of the room and drawn into the chamber 9 for recirculation. Fresh air may also be conducted to the chamber 9 through an auxiliary inlet 14 located in the side of the air chamber 9 adjacent the inlet 10 and also equipped with a filter element 15.

The fresh air inlet 14 may be connected directly with the outside atmosphere through the side of the building or to some suitable source of fresh air by means of a duct 16.

Any suitable means may be provided for controlling the ratio of the air entering the chamber 9 through its recirculation inlet 10 and its fresh air inlet 14, and for purposes of illustration, a damper 17 has been shown in the duct 16 to effect this function.

Mounted in the air chamber 9 between the inlet and outlet openings 10 and 14 is a heat exchanger 18. This heat exchanger extends transversely across the stack or air chamber so that all air flowing from the inlet to the outlet must pass through the same. It consists of spaced headers 19 and 20 connected by a series of tubes 21 on which fins 22 are mounted. An inlet pipe 23 connects with the header 19 and an outlet or exhaust pipe 24 connects with the header 20.

Beneath the heat exchanger is an air circulating means in the form of an air blower 25. This blower 25 is mounted within a casing provided by a sheet metal wall 26 bent to substantially U-shape with the upper ends thereof extending

across the space between the front and back walls of the stack or air chamber and attached to the headers 19 and 20, and the medial portion 26 thereof shaped to provide a spiral housing for 5 the blower to direct the air flow induced thereby upwardly through the heat exchanger.

As best shown in Figure 3, the lower portion of the wall 26 does not extend across the full depth of the stack or air chamber. One edge thereof 10 is spaced from the adjacent wall of the stack so that air entering the same through the inlet 10 or 14 has unrestricted access to the center of the blower.

The blower is driven by means of a fluid pressure motor 27 suitably mounted in the stack or air chamber and attached to the shaft of the blower. To drive the fluid pressure motor the exhaust from the heat exchanger is utilized and to this end the exhaust or outlet pipe 24 leading 20 from the heat exchanger is connected by piping 28 to the inlet of the fluid pressure motor.

The outlet of the fluid pressure motor has a pipe 29 connected thereto which leads down into the return line 30 attached to the bottom wall 31 of the stack or air chamber 9. The bottom wall 31 is pitched toward its connection with the return line 30 so as to drain all condensate accumulating within the unit down into the return line.

30 As hereinbefore noted, each room of the home or building in which the system is installed has one or more of the conditioning units 8 arranged to supply conditioned air thereto, and it is to be observed that except for the short ducts which 35 supply fresh air to the units when it is found desirable or necessary, the system is substantially ductless, and if the fresh air inlets open directly through the outside walls of the building, it is completely ductless.

40 The temperature modifying medium circulating through the heat exchangers of the different units is preferably water, although any other suitable liquid may be employed.

To this end, the inlets 23 of the heat exchangers 45 of all of the units are connected with a feed line 35. The feed line is connected to the outlet of a force pump 36 through a pressure reducing valve 37. The pump 36, which is driven by an electric motor 38, is arranged to recirculate the water in 50 the system or may be supplied with fresh water from the regular fresh water source of the building. The direct supply to the pump is provided by a pipe line 39.

The pipe line 39 has two valves 40 and 41 connected with it in parallel. Both valves are automatic and controlled electrically by suitable control mechanism 42 and 43, respectively. The valve 40 is the hot water control valve, and the valve 41 is the cold water control valve.

60 Through the valves 40 and 41 the pipe line 39 is connected respectively with a hot water boiler 44 and/or a cold water tank 45. The hot water boiler 44 is of any suitable design and the cold water supply tank 45 may be in the form of an ordinary tank provided with a cooling coil 46 supplied with refrigerant from a refrigerating unit 47. Both the hot water boiler and the cold water supply tank have a common inlet pipe 48 which connects with the fresh water supply of the 65 building through a pipe 49 equipped with a hand control valve 50, and also with the return line 51 to which all of the return pipes 38 of the several conditioning units connect. Obviously, only 70 one of the two valves 40 and 41 is open at any given time.

The controls for the valves 40 and 41 function at the dictation of a central control unit 52 located in one of the rooms of the building. The construction of this control unit forms no part of this invention and is therefore not shown in detail. It is sufficient to note that this unit embodies a thermostat and a humidistat. The thermostat is connected to the controls 42 and 43 by means of wires 53 and 54, respectively.

5 The thermostat of the unit 52 is so arranged 10 that for winter heating, the need for an increase in temperature closes a circuit for the control unit 42 which responds to open the valve 40, and in summer the thermostat of the control unit 52 acts whenever the temperature exceeds 15 a predetermined maximum to cause the control 43 to function and open the valve 41.

Humidification is provided by sprays of water 20 in the individual units. For this purpose, a spray nozzle 55 is mounted in each unit beneath the 25 heat exchanger so that when in operation it directs a spray of water up against the heat exchanger. The condensate flows down onto the bottom wall of the unit where it is collected to drain down into the pipe 30.

25 The spray nozzle 55 is supplied with water from the feed line 35 through a pipe connection 56 provided with a pressure responsive valve 57. The valve 57 is adjusted so as to open when the pressure on the feed line 35 exceeds that maintained by the pressure reducing valve 37. To illustrate, assuming that the pressure reducing valve 37 is set to open at fifty pounds per square inch, the valve 57 in each of the several units will be adjusted so as to remain closed until the 35 pressure in the feed line 35 reaches at least fifty-two or fifty-three pounds per square inch. Hence, unless the pressure of the feed line is increased, the valves 57 of all of the units will remain closed and the humidifier sprays 55 will be inoperative.

To increase the pressure of the feed line 35 and effect humidification, a second pressure reducing valve 58 and a humidity control valve 59 connected in series are connected in shunt with 45 the pressure reducing valve 37. The control valve 59 is normally closed and is controlled by mechanism 60 electrically responsive and controlled by the humidistat located within the control unit 52 with which it is connected by a conductor 61.

50 In the event an increase in humidity is required, the response of the humidistat in the control unit 52 to this condition causes the control mechanism 60 to function and open the valve 59. With the valve 59 open, the pressure reducing valve 58 which is set to open at a higher pressure than the valve 37, which for purposes of illustration may be fifty-five pounds per square inch, will open, the pump 36 maintaining a pressure sufficiently high to insure the opening of the 60 valve 58. The pressure on the feed line 35 is thus stepped up from fifty to fifty-five pounds per square inch, and as a consequence, all of the valves 57 controlling the supply of water to the humidifier sprays automatically open.

65 Upon increase in humidity as a result of the operation of the humidifier sprays, the control unit causes the mechanism 60 to function to close the valve 59 thus bringing the pressure on the feed line 35 back to fifty pounds, which pressure 70 is insufficient to maintain the valves 57 open. The sprays 55 are thus shut off.

75 It is to be observed that a manually controlled valve 65 is connected with the inlet pipe 28 of each conditioning unit so that the flow of the 75

temperature modifying medium through the heat exchanger and also the speed of the blower in each individual unit may be separately controlled.

The exposed type of conditioning unit illustrated in Figure 4, which is particularly suitable for installations in homes and buildings already in use, comprises an upright casing or compartment 70 of neat external appearance provided with a recirculation air inlet 71 at its extreme bottom so as to take air directly off of the floor, and a fresh air inlet 72 connectible with a source of fresh air. A sliding valve structure 73 is provided to simultaneously control the degree of opening of both air inlets. This valve mechanism is so arranged that when one air inlet is open the other is closed, and vice versa.

Above the air inlets and extending across the entire horizontal cross section of the casing or compartment 70 is an air filter element 74 through which the air entering either or both inlets must pass to reach the blower 75. The blower 75 is mounted within a blower casing 77 open at both sides to permit the flow of air into the center of the blower and having its outlet 78 arranged to discharge the air up through a grilled outlet 79 at the top of the unit.

The grill 80 for the outlet has inclined vanes, as shown, and is hingedly mounted to permit the same to be swung upwardly to provide different angles of deflection for the air discharged from the unit.

The blower 75 is actuated by a fluid pressure motor 81, which like the motor 27, is driven from the exhaust of the heat exchanger 82 mounted in the outlet 78 of the blower casing, the exhaust of the heat exchanger being connected with the motor 81 by piping 83.

The intake of the heat exchanger has a feed line 84 connected thereto and the exhaust from the motor 81 and also a drip chamber 85 are connected with a return line 86. A spray nozzle 87 is also provided which is connected to the feed line 84 through a pressure control valve 88.

For purposes of clarity, the various pipe connections of the unit have been shown located entirely outside the unit, but as will be readily apparent, these may be so disposed as to be entirely within the casing or compartment with the feed and return lines 84 and 86 entering the same through the bottom.

From the foregoing description taken in connection with the accompanying drawings, it will be readily apparent to those skilled in the art, that this invention provides a ductless air conditioning system and that by reason of the fact that no ducts are necessary a materially simplified design and construction having many advantages over past and existing air conditioning systems is obtained.

60 What I claim as my invention is:

1. In an air conditioning system, a heat exchanger, a blower to induce a flow of air past the heat exchanger, a fluid pressure motor to drive the blower, a humidifier spray, piping for conducting a liquid temperature modifying medium under pressure to the heat exchanger, the fluid pressure motor and the humidifier spray, whereby a common medium renders the heat exchanger effective and provides motive power for the fluid pressure motor and supplies liquid for the humidifier spray, and an automatic valve in the piping to control the functioning of the humidifier spray without affecting the supply of the liquid temperature modifying medium to the heat exchanger and the fluid pressure motor.

2. In an air conditioning system, a heat exchanger, a blower to induce a flow of air past the heat exchanger, a fluid pressure motor to drive the blower, a humidifier spray, piping for conducting a liquid temperature modifying medium 5 under pressure to the heat exchanger, the fluid pressure motor and the humidifier spray, whereby a common medium renders the heat exchanger effective and provides motive power for the fluid pressure motor and supplies liquid for the humidifier spray, and a pressure responsive valve in said piping ahead of the humidifier spray to prevent the flow of liquid to the spray except when the pressure in the piping exceeds that for which the pressure responsive valve is set. 10 15

3. In an air conditioning system, conditioning units arranged to discharge conditioned air directly into different rooms to be supplied, each conditioning unit including a heat exchanger and a humidifier spray, a common feed line leading 20 from a remote central point to the heat exchangers and the humidifier sprays of all of the units to conduct a liquid temperature modifying medium under pressure thereto, pressure responsive valves interposed between the humidifier 25 sprays and the feed line adapted to open and connect the humidifier sprays with the feed line when the pressure on the feed line reaches a predetermined value, and means controlled by a humidistat within one of the rooms to be supplied 30 for controlling the pressure on the feed line.

4. In an air conditioning system for supplying tempered and conditioned air to a room, means for inducing a flow of air into said room, a heat exchanger arranged to give the air flowing into 35 the room a predetermined temperature, a humidifier spray for increasing the relative humidity of the air flowing into the room, a common feed line to supply a liquid temperature modifying medium under pressure to the heat exchanger 40 and the humidifier spray, a pressure responsive valve controlling the connection of the humidifier spray with the feed line and arranged to open when the pressure on the feed line reaches a predetermined value, means for normally maintaining a predetermined pressure on the feed line, and means operable to effect an increase in pressure 45 on the feed line.

5. In an air conditioning system for supplying conditioned air to the living quarters of a home, the combination of a conditioning unit located in juxtaposition to one of the living quarters of the home and arranged to discharge conditioned air into said living quarters, said unit including a heat exchanger, a humidifier and fluid pressure 50 operated means for circulating air, a source of liquid temperature modifying medium located in a non-living quarter section of the home, a force pump having its inlet connected with said source, piping leading from the outlet of the pump to 55 said unit for simultaneously supplying the liquid temperature modifying medium to the heat exchanger, the humidifier and the fluid pressure operated air circulating means for giving effect to all of said elements, a common drain for carrying off all of the spent liquid temperature modifying medium at atmospheric pressure and any condensate which forms in the unit, and automatic valve means for turning on and shutting off the flow of the liquid temperature modifying 60 medium to the humidifier in accordance with humidity requirements without in anywise affecting the supply of the liquid temperature modifying medium to the heat exchanger and the fluid pressure operated air circulating means. 65 70 75

6. In an air conditioning system, the combination of a heat exchanger having an inlet and an outlet, a blower for inducing a flow of air through the heat exchanger, a fluid pressure motor for driving the blower, means for conducting a temperature modifying medium under pressure to the inlet of the heat exchanger, means for conducting the fluid temperature modifying medium from the outlet of the heat exchanger to the inlet of the fluid pressure motor so that said motor is operated from the exhaust of the heat exchanger, the exhaust from the motor discharging into the atmosphere, and a common drain for draining off the fluid temperature modifying means exhausted from the fluid pressure motor and for draining off condensate which drips from the exterior of the heat exchanger.

7. In an air conditioning system, the combination of a heat exchanger having an inlet and an outlet, a chamber located beneath the heat exchanger for collecting condensate which drips from the heat exchanger, a fluid pressure operated means mounted inside said chamber for inducing a flow of air through the heat exchanger, means for feeding a fluid temperature modifying medium under pressure to the inlet of the heat exchanger, means for conducting the fluid temperature modifying medium from the outlet of the heat exchanger to said fluid pressure operated means so that the fluid pressure operated means is driven by the exhaust from the heat exchanger, the exhaust from the fluid pressure operated means discharging to the bottom of said chamber, and means for draining off all spent fluid and condensate from said chamber.

8. In an air conditioning system, the combination of a heat exchanger having an inlet and an outlet, a blower for inducing a flow of air through the heat exchanger, a fluid pressure motor for driving the blower, means for injecting moisture into the air stream induced by the blower to provide humidification, means for feeding a fluid temperature modifying medium to the inlet of the heat exchanger, means for conducting the fluid temperature modifying medium from the outlet of the heat exchanger to said fluid pressure motor so that the motor is driven from the exhaust of the heat exchanger, the spent fluid temperature modifying medium from the motor discharging into the atmosphere, and a drain for said spent fluid temperature modifying medium having means for collecting and draining off the excess moisture injected into the air stream.

9. In an air conditioning system, the combination of a heat exchanger having an inlet and an outlet, a blower for inducing a flow of air through the heat exchanger, a fluid pressure motor for driving the blower, means for introducing water for humidification into the air stream induced by the blower, means for feeding water of a predetermined temperature under pressure to the inlet

of the heat exchanger, means for conducting the water from the outlet of the heat exchanger to the fluid pressure motor so that the motor is driven from the exhaust of the heat exchanger, the exhaust from the fluid pressure motor discharging into the atmosphere, and drain means for collecting and draining off the humidification water which is not absorbed by the air stream and the exhaust from the blower motor.

10. An air conditioning unit comprising, a heat exchanger having an inlet and outlet for the admission and discharge of water under pressure, a blower for inducing a flow of air through the unit, a water turbine for driving the blower, means for conducting water from the outlet of the heat exchanger to the inlet of the turbine so that the turbine is driven from the exhaust of the heat exchanger, means for injecting water for humidification into the air stream induced by the blower, the excess of which drips down to the bottom of the unit, and means at the bottom of the unit for collecting and draining off all excess and spent water used in the operation of the unit.

11. In an air conditioning system for dwellings, the combination of a conditioning unit located in juxtaposition to one of the living quarters of the dwelling and arranged to discharge conditioned air into said living quarters, said unit including a heat exchanger, a humidifier and fluid pressure operated means for circulating air, a source of liquid temperature modifying medium located in a non-living quarter section of the dwelling, a force pump having its inlet connected with said source, piping leading from the outlet of the pump to said unit for supplying the liquid temperature modifying medium under pressure to the heat exchanger, the humidifier, and fluid pressure operated air circulating means for giving effect to all of said elements, and a common drain for returning all of the spent liquid temperature modifying medium at atmospheric pressure and any condensate which forms in the unit back to said source.

12. In an air conditioning system, a conditioning unit including a heat exchanger adapted to have a liquid temperature modifying medium circulated therethrough, a turbine motor, an air impeller driven thereby and arranged to move air through the heat exchanger, the discharge of the turbine motor being to the atmosphere, a source of liquid temperature modifying medium under pressure, means for conducting the liquid temperature modifying medium under pressure to the inlet of the heat exchanger, means for conducting the liquid temperature modifying medium from the outlet of the heat exchanger to the inlet of the turbine motor, and means for returning the spent liquid temperature modifying medium at atmospheric pressure back to its source.

RICHARD C. JEPERTINGER.
